UNITED STATES PATENT OFFICE.

ALBERT SCHOENHUT, OF PHILADELPHIA, PENNSYLVANIA.

DESIGN FOR A TOY FIGURE.

No. 39,775.

Specification for Design.

Patented Jan. 19, 1909.

Application filed November 4, 1908. Serial No. 461,093. Term of patent 14 years.

To all whom it may concern:

Be it known that I, ALBERT SCHOENHUT, a citizen of the United States, and a resident of Philadelphia, Pennsylvania, have invented a certain new, original, and ornamental Design for a Toy Figure, of which the following is a specification, reference being had to the accompanying drawings, forming part thereof, in which—is a rear elevation, showing my new design for a toy figure in the form of Santa Claus.

I claim:

The ornamental design for a toy figure, as shown.

ALBERT SCHOENHUT.
